UNITED STATES PATENT OFFICE

WILFRID V. N. POWELSON AND WARREN TRAVELL, OF NEW YORK, N. Y.

MEANS FOR MOORING AND HOUSING AIRSHIPS

Application filed September 21, 1921. Serial No. 502,127.

This invention relates to improvements in means for mooring and housing airships.

According to present practice, airships are housed in large buildings, called hangars, erected above the surface of the ground. Airships are moved into and out of these hangars by hand, through large doorways or openings at the ends, requiring a very large number of men for the larger airships. Accidents to airships in entering and leaving these hangars are not infrequent, due to the inability of human hands to hold the airships securely in position, by reason of the very great forces that are frequently applied to the surface of the airship by the wind. All hangars at present in use have a very large cubic capacity as compared with the cubic capacity of the airship; also hangars built to accommodate an airship of a given size may not be increased to accommodate a larger airship without practically destroying the building.

It is an object of this invention to provide housing facilities which are free from the above mentioned defects. We propose to construct an airship shelter preferably either wholly or partly under ground, conforming to the shape of the airship, and providing opportunities for inspection and repair that are not available in any type of hangar now known to the art, into and from which the airship is moved vertically under mechanical control, with freedom from the dangers heretofore incident to entrance and exit.

35 A low structural roof movable on horizontal tracks is provided to cover such a pit when excavated below the surface of the ground, and other methods for securing protection from the elements are also provided herein, so that the safety of the house and its contained airship is absolute against destruction by high winds. In time of war a large hangar as built in the past offers a well marked target to the enemy for destruction. 40 One constructed according to this invention not only is much better protected but may be easily camouflaged so as to escape observation. Moreover the cost of construction is greatly reduced; and such a pit may be enlarged at any time to provide for airships of

larger size, readily and without any destruction of existing structures.

Our invention provides for a modification of this shelter pit in which the pit is shallow, being of such depth that only the 55 lower part of the airship is contained therein, the upper portion of the envelope of the air ship being used as a roof. Strips of weather-proof material between the envelope and the edges of the pit complete the protection against rain, snow, etc. Protection against the destructive force of wind is obtained for airships thus housed in shallow shelter pits, by means of inclined planes so constructed and so located that wind is deflected upward over the protruding airship. 60

For entrance of the airship into the shelter pit, and for safely handling it during its exit therefrom, suitable vertical ropes leading to winches are provided. This invention also 70 provides a suspended cradle in which the airship rests when within the shelter pit, and ropes or other means for securely holding it in position while thus housed.

For handling an airship on its arrival at 75 a station, and for controlling its descent into the shelter pit, its berthing, removal and launching, the invention provides safe, efficient and economical means closely correlated with each other and with the housing improvements already described; and all taken together constitute a system for the handling of airships at a station which is not only new and useful, but which, by eliminating the risk and great expense hitherto attendant upon 80 such operations, will assist greatly in making the use of airships commercially successful.

For such safe and efficient handling of an airship, we provide a mooring tower at one end of the shelter pit, with which may be 85 associated another tower movable on a track which encircles the pit. Another modification of the invention is the arrangement of a shelter pit with a track encircling it, and two mooring towers movable thereon, the 90 track being so located with respect to the pit that after an airship has been moored between the towers, the towers may be moved on the track to such a position that the airship is directly over the shelter pit. Within 95 100

the space enclosed by the tower track, a number of shelter pits may be constructed. Arrangements of towers, tower tracks and shelter pits are illustrated in the accompanying drawings as part of our invention.

After an airship has been attached to a mooring tower, it may be lowered for berthing and raised for launching on its flight by apparatus of various kinds, a number of which are illustrated in the drawings. The point of attachment may be to a carriage movable along a track up and down the face of the tower, and this track may be extended at the end of the shelter pit, thus forming a continuous vertical way for the attachment carriage from a point near the top of the tower to a point corresponding with the berthing position of the airship within the shelter pit. Instead of using such a travelling carriage, the airship may be raised and lowered under control by a "burtoning" method, somewhat similar to that commonly employed for handling cargo freight to and from vessels. This method makes use of two lines so attached that by the proper hauling in and paying out of which, the airship may be raised, lowered, or moored in any position under control. Still another arrangement, provided for in this invention and more especially adapted for use in connection with smaller sized aircraft, is a telescopic mast, of which the upper section to which the craft is attached may be moved up and down within a fixed outer section.

Such mooring towers, with their means for raising and lowering airships under control are also useful for the mooring and handling of airships under mechanical control, aside from their use in connection with shelter pits, or with other hangar or berthing device which is open at the top for receiving the airship, and for raising it therefrom. The invention also provides for the use of a cradle upon which the airship may be lowered and to which it may be securely fastened.

To make this method of handling airships by mooring towers safe and efficient, the invention provides means for maintaining the towers and the moored airship head-on to the wind at all times; for limiting the side pull in the attachment line leading to the tail tower; and for stabilizing the airship while thus moored. The cradle last mentioned may be either stationary or supported on wheels running on a track, thus constituting a cradle car. Preferably these tracks are laid in a circle with the mooring tower at the center, so that after an airship has been brought up and moored to a tower head-on to the wind, the cradle car may be moved around its track to a position beneath the airship, after which, the ship may be lowered thereon and attached thereto. The invention further provides for the moving of the

cradle car with an airship berthed thereon, by means of a transfer car, to a position within a hangar which may be located at a distance from the mooring tower, or towers.

In the practical application of the invention thus set forth, various devices may be employed in substitution for those which are herein shown as illustrating the principles involved; and variations may be made in many respects without departing from the scope of the invention. It is intended that the patent shall cover by suitable expression in the appended claims whatever features of patentable novelty exist in the invention disclosed.

The accompanying drawings are:

Fig. 1, plan of shelter pit with its roof removed to one end and shown only in part. At the other end of the pit is a mooring tower.

Fig. 2, side elevation of above with the pit shown in section.

Fig. 3, cross-section of Fig. 1 on line 3—3, but covered with roof.

Fig. 4, cross-section of a shallow shelter pit with a covering comprising the upper portion of the airship and side strips.

Fig. 5, side elevation on a larger scale of the mechanism for moving the roof shown in Fig. 3.

Fig. 6, end view of the same.

Fig. 7, plan showing several shelter pits located radially about a central mooring tower with a second mooring tower movable on a track encircling these shelter pits.

Fig. 8, side elevation of above its medial section.

Fig. 9, side elevation on a larger scale of the top of the central mooring tower.

Fig. 10, plan showing two mooring towers on a track encircling a shelter pit, with spacer cars between the towers and a roof removed sidewise from over the pit.

Fig. 11, side elevation of the same, the pit being shown in medial section.

Fig. 12, cross-section of middle part of Fig. 10, on line 12—12.

Fig. 13, side elevation on a larger scale of a spacer car.

Fig. 14, plan showing a circular shelter pit with revolving roof, a mooring tower at its center, another mooring tower movable on a track encircling the pit, and an opening through the roof for the entrance and exit of airships.

Fig. 15, side elevation of the same, the pit and its roof being shown in section on line 15—15 of Fig. 14.

Fig. 16, side elevation of a mooring tower and section end portion of a shelter pit, with a way for a mooring carriage extending down the face of the tower and the end of the pit.

Fig. 17, front view on a larger scale of the way shown in Fig. 16.

- Fig. 18, plan on a still larger scale in section on line 18—18 of Fig. 17.

- Fig. 28, side elevation of same in medial 30 section.
- Fig. 29, end elevation on a larger scale of airship and cradle car of Fig. 27.
- Fig. 30, plan showing a transfer car movable on a circular track about a central mooring 95 tower, a cradle car with track therefor on the cradle car and leading away therefrom, and an airship suspended in a cradle on the cradle car.
- Fig. 31, side elevation of same with track 40 pit shown in medial section.
- Fig. 32, end elevation to a larger scale of a detail of Fig. 31.
- Fig. 33, side elevation of movable mooring mast with sliding collar.
- 45 Fig. 34, plan of same in section on line 34—34 of Fig. 33.
- Fig. 35, plan of mast on a larger scale in section on line 35—35 of Fig. 33.
- 50 Fig. 36, elevation of a fraction of same in section on line 36—36 of Fig. 35.
- Fig. 37, plan on a larger scale of mechanism for controlling the movements of sliding collar and mooring connection.
- 55 Fig. 38, side elevation of same.
- Fig. 39, side elevation of stationary, telescopic mooring mast.
- Fig. 40, plan on a larger scale of the mast of Fig. 39, in section on line 40—40 of Fig. 39.
- 60 Fig. 41, side elevation of movable mooring tower with vane control.
- Fig. 42, elevation on a larger scale of top of tower in medial section.
- Fig. 43, plan of control vane of Fig. 41.
- 65 Fig. 44, side elevation of same.
- Fig. 45, elevation of same on a larger scale, in section on line 45—45 of Fig. 43.
- Fig. 46, plan of details of same showing collector rings and wiring diagram, in section on line 46—46 of Fig. 45.
- Fig. 47, side elevation of tower moving means.
- Fig. 48, end elevation of same.
- Fig. 49, plan showing top of mooring tower and device for controlling movement of tower, actuated by change in position of tail rope.
- Fig. 50, elevation of same in section on line 50—50 of Fig. 49.
- Fig. 51, elevation like Figure 50 showing a detail on a larger scale.
- Fig. 52, elevation in cross-section on line 52—52 of Figs. 50 and 51.
- Fig. 53, wiring diagram for tower moving device shown in Fig. 49.
- Fig. 54, elevation of a fixed mooring mast with a universal-jointed mooring attachment and a means for stabilizing an airship by the use of a chain or suspended weights.
- Fig. 55 and 56, respectively, plan and elevation on a larger scale of the mooring attachment of Fig. 54.
- Fig. 57 and 58 are views on a larger scale of the stabilizing means shown in Fig. 54.
- Fig. 59 shows in elevation an airship 95 moored to a travelling carriage on a rotatable tower, together with means for stabilizing the airship by the use of liquid, the weight of which is added to or removed from the airship.
- Fig. 60 is a side elevation and Fig. 61 a plan on larger scale of the stabilizer shown in Fig. 59.
- Fig. 62 is an elevation in section on a larger scale of portions of this apparatus.
- Fig. 63 is a side elevation of a roof covering and support.
- Fig. 64 is a side elevation of a portion of same enlarged.
- Fig. 65 is a sectional view on line 65—65 of Fig. 63, enlarged.
- Fig. 66 is a sectional view on line 66—66 of Fig. 64, enlarged.
- In the drawings, Figs. 1, 2 and 3 show an airship 1 housed in a shelter pit 7 located below the general surface of the ground. This shelter pit may be covered by a roof 23 movable on tracks 22. At one end of the shelter pit there is shown in Figs. 1 and 2 a tower 9 revolving on circular track 10 and having on one face a vertical way 21 along which is movable a carriage 13. The movement of this carriage is controlled by ropes 14 leading to a hoisting machine 16. A flexible connection of rope 18 attached to the bow end of the airship 1 passes around a sheave 171 on the carriage 13 (for greater detail see Figures 17 and 18); thence around a sheave 12 at the top of the tower and to a control means or hoisting engine. The tower may be prevented from 110 115 120 125 130

tipping over under stress by having a track 471 made with flange facing downward, and providing wheels 470 to engage under it as shown in Figures 47 and 48, or other suitable means may be used. After the airship is thus attached to this movable carriage of the mooring tower, the airship may be raised and lowered under control. An extension 21' of the way 21, down one end of the shelter pit, permits travel of the carriage 13, with the ship 1 between lower and upper positions indicated by full lines and dotted lines. Ropes 20 leading to the hawser holds 19, or capstans, fasten the airship 1 securely in place after it has been lowered into the suspended cradle 36 within the shelter pit. At the suspension ends of this cradle 36 are springs 37 for providing elasticity to said cradle. A hoisting machine 34 controlling the ropes 20 provides means for additional control of the airship during the lowering and elevating process. Fig. 4 shows a modification of the shelter pit where the airship 1 is only partly contained therein. Instead of a large and rigid roof 23 as shown in Fig. 3 there is shown in Fig. 4 a means of covering the shelter pit, which comprises the upper portion of the airship 1 itself and weather-proof strips 42 covering the space between the said airship and the sides of the pit. Flashing strips 41 attached to the sides of the airship may be used for making the connection between the strips 42 and the airship weather-tight.

Figs. 5 and 6 show means for moving roof 23 along its tracks, comprising wheels 51 turning on axles 52 and driven through gearing 53, 54, 55, 56, 57, by motor 58. Similar means may also be used for revolving the mooring tower 9 on its circular track.

Figs. 7 and 8 show a rigid tower 71 at the center of a track 73 laid in a large circle, having a radius greater than the length of the airship 1 to be moored. On this circular track there is movable a second mooring tower 9. There are a number of shelter pits 72 built along radial lines within said circular track 73. These are provided with movable roofs 23. Flexible connections 80 fasten the airship between the towers 71 and 9. A more detailed view of the point of attachment of this flexible connection to the top of tower 71 is shown in Fig. 9. A second set of ropes 81 lead from the head and tail ends of the airship to control means 34 located at the bottom of the shelter pit. By paying out ropes 80 and hauling in ropes 81 a safe means is provided for the lowering of the airship 1 from its moored position at the top of the tower to its berthed position within the shelter pit.

Figs. 10, 11, and 12 show a shelter pit 72 conforming in general in its horizontal cross-sections to the horizontal cross-sections of airship 1, with space allowed for clearance and workmen between sides and bottom of

shelter pit and the airship. Around this shelter pit there is a horizontal circular track 100 on which are movable two towers 9. A number of spacing cars 106 (see Fig. 13) may be used for maintaining the mooring towers 70 9, a fixed distance apart, at opposite ends of the diameter of the circle on which they travel. A roof 101 over the shelter pit is movable transversely as regards the shelter pit on tracks 105. As represented in Figures 75 10 and 12 this is in two sections which meet over the middle of the pit, comprising truss beams running on wheels 102 and having extensions 103 to the rear to counterbalancing weights 104, so that on a cantilever principle each roof section covers half of the span with the projecting part overbalanced by the weight.

Figs. 14 and 15 show an annular shelter pit 153 having a radius greater than the length of airship 1 to be housed. A large circular roof covers this shelter pit, this roof being supported on a central pier 152 and on circular track 142 extending around the pit and concentric therewith. A mooring tower 150 at the center of the shelter pit is attached to the roof and revolves therewith. A second mooring tower 9 is movable on the circular track 100. In operation, an airship 1 is brought up head-on to the wind to the central mooring tower 150 and attached thereto, after which the tail tower 9 is moved around to the leeward of the airship and the connection 80 is made therewith. An opening 140 is provided in the large circular roof with 100 movable covering 141 over this opening, which covering may be moved back to the dotted line position, thus permitting a clear opening through the roof for the vertical entrance and exit of airships at any part of the 105 circular pit. A pit of this description may be used for the housing of a large number of airships, with only a single pair of mooring towers.

Figs. 16, 17 and 18 show in greater detail 110 the revolving tower 9 at the end of pit shown in general plan and elevation Figs. 1 and 2. The tower 9 on being revolved so as to bring the way 21 in line with its extension 21' is then fixed in that position by any suitable 115 means. After the mooring tower is thus fixed, the rope 14 is led downward from the carriage 13 around sheave 161 which is fixed at the end of the shelter pit, and thence around sheave 162 to its control means, the 120 winch 16. With such a carriage traveling up and down the vertical way 21, 21' on the tower and at the end of the shelter pit, it is possible to move an airship under control between its moored position and its berthed 125 position within the shelter pit.

Figs. 19, 20, 21, 22, 23, 24, 25 and 26 show means for protecting an airship from the forces of the wind when such airship is housed in a partial enclosing structure. In- 130

clined surfaces 190 may be built on a number of separate structures around a shelter pit 7 shown in Figs. 19 and 20 or such inclined surfaces may be constructed as part 5 of the housing structure 230 as shown in Figs. 22, 23, 24, 25 and 26, where they are marked 190' and 190''. In Figs. 22 and 23 the housing structure is shown only along each side of the lower portion of the airship 10 when held suspended in the cradle 36 between the structures, in which case other and separate means may be provided if desired for protecting the ends of the enclosed space from the elements. In Figs. 15 24, 25 and 26 the inclined surfaces are shown as extending entirely around airship 1, which is held suspended in the space enclosed by such structure. Fig. 21 shows on 20 larger scale a construction which provides for the lowering of the inclined plane 190 to the dotted horizontal position when so desired, the brace 210 and the plane surface 190 revolving about the hinges 212 and 211. By thus lowering the inclined planes when 25 not required a practically level space is provided around the shelter pit for the handling and manipulation of the airship by man power on the ground.

Figs. 27, 28 and 29 show a tower 9 revolvable on track 10 having a vertical way 21 along which a carriage 13 is movable and to which carriage an airship 1 may be attached. On the ground is a circular track 270 concentric with the mooring tower on which track 25 there is movable a cradle car 280. The airship 1 on being moored to the tower in dotted position, head to the wind, may be lowered under control to the full line position resting in suspended cradle 36 on the cradle car 40 and fastened down to the cradle car by ropes, after the cradle car has been brought to a position beneath the airship. If desired, protection from the elements for the lower part of the ship may be obtained by the use 45 of weatherproof strips 42 covering the space between the airship and the sides of the cradle car. Means for moving the cradle car on its track are similar to that shown in Figs. 5 and 6 for moving roof 23 along its track.

50 Figs. 30, 31 and 32 show a similar arrangement of central tower 9 and circular tracks 270 except that here the cradle car 280 rests on a transfer car 310 which runs on circular tracks 270, and is itself movable along any track 271 of which a number may be provided on different radii, thus continuing along the surface of the ground to any point desired. The transfer car 310 is movable on its 55 circular track 270 by means already described to a position below the moored position of airship 1. After the airship is lowered from such moored position to its berthed position on the cradle car 280' it, with its cradle car, may be moved off from the trans-

fer car 310 to a point within a hangar if so desired.

Figs. 33, 34, 35 and 36 refer to a mooring mast herein considered as a specific form of tower. This mast 330 is movable on track 331 and has a collar 332 which is capable of a sliding motion up and down said mast, such motion being controlled by ropes 333 leading to a hoisting machine 334. This hoisting machine 334 as shown has a drum 370 driven 35 through a gearing 371 by an electric motor 372, and may be of any well known or suitable type. A similar hoisting machine 335 is used for controlling the rope 80 which attaches the airship to the mast. This rope 80 39 passes around a sheave 360 which is carried by a ring 361 revolvable around the collar 332. If desired, anti-friction rollers 362 may be used between said ring and said collar. The rope 80 after passing around the 45 sheave 360 is led upward around a sheave 336 carried by a rooster 337 revolvable about the central axis of the mast, and having an opening through its center through which rope 80 may be led downward to its control means 335. Fig. 35 shows in greater detail a method of constructing a mast with an inner cylinder 351 concentric with the outer cylinder 352 and having web girders 353 between. Any other suitable method may be used for 95 obtaining a mast of sufficient strength and rigidity.

Figs. 39 and 40 show a mooring mast with airship 1 moored thereto having one portion of the mast 390 telescoping within a second portion 391. This inner section may be raised and lowered by means of ropes 392 leading from a controlling means 393 similar to that shown in detail in Figs. 37 and 38. The rope 80 connecting the airship to the top of the 100 telescoping section 390 is shown passing over a curved surface 393 at the top of said 390, and thence downward around fixed sheave 394 to its control means 395, which also is similar to that shown in Figs. 37 and 38. 105 Guy ropes 396 may be used for staying the lower section of the mast. Fig. 40 shows a design of the inner mast made up of two concentric cylinders 401 and 402 with web girders 403 between. 110

Fig. 41 shows a mooring tower 9 movable on track 10 and having at its top a vane 410 which, as moved by the wind, controls the movement of tower 9. The wind tends to 115 maintain the airship always in a position directly to the leeward of a tower to which it is moored. For certain purposes, as for settling the ship into a cradle on tracks as in Figures 27-31, or to bring its tail end into proximity to another tower as in Figs. 7, 10, 120 or 14, it may be desired to move the head mooring tower so that the tail of the ship will be pointed toward that other tower by the wind; or so that the ship's body will lie over a particular area of ground. The upper por- 125

tion of a head tower is shown in greater detail in Figs. 42, 43, 44, 45 and 46. The vane 410, revolvable about the central pin 450 carries with it an insulated ring 451 to which 5 are attached current collectors 452. These collectors on the rotation of the vane 410 make contacts with collector rings 461 which rings are connected by wiring to a source of electrical power 462 and to the motor 463 which 10 moves the tower on its track. This motor with its associated mechanism is shown in greater detail in Figs. 47 and 48, and may be of any well known and suitable type. Fig. 46 shows diagrammatically a wiring diagram 15 indicating the method of working of this tower moving device so that upon the swinging of the vane 410 in either direction a current is sent through the motor 463 in suitable direction to propel the tower along its track 20 until the face of the tower is square to leeward of the ship, at which position the brushes 452 rest upon the insulation 464 between the two segments 465 which constitute terminals of motor 463. Fig. 45 shows a shield 453 protecting the electrical apparatus from the 25 weather. This tower moving device may also be used on a head tower for maintaining the point of attachment of the rope 80 always on the leeward side of said tower and facing 30 the bow end of the airship. It also may be used on a tail tower for keeping that tower in the direction from the head tower in which the wind is blowing the ship. Fig. 42 shows 35 a concave receptacle comprising a funnel-shaped device 421 through which the attachment rope 80 may be led around a sheave 422 and thence downward to the control means 11.

Figs. 49, 50, 51 and 52 and 53 refer to a 40 means for controlling the movement of a tail mooring tower so as to automatically maintain it in a position directly in the rear of an airship moored thereto. The tower 9 movable on a circular track 73 as shown in Figs. 45 and 50 has moored thereto an airship 1 by a 45 rope 80 leading over a sheave 12 and thence to a control means 11 not shown. When the tail end of the airship swings to one side, causing its axis to take a position making 50 an angle with the theoretical line joining the centers of the two mooring towers 71 and 9 of Figs. 7 and 8 the tail rope 80 is drawn correspondingly to one side, pressing a pair of floating segmental conductor rings 520 and 550, which are really motor terminals, to that 55 side and into contact with the fixed ring 521 and 511 whose segments at opposite sides are of opposite polarity for delivering current to the motor in one direction or the opposite. 60 When free the inner rings 520 and 510 are brought back to their normal position concentric with rings 521 and 511 by means of springs 522 or other equivalent devices. These rings 510, 511; and 521, 520; are insulated and connected by wiring to a source 65 of electric power 462, and to the tower moving motor 463 as indicated in the wiring diagram shown in Fig. 53, so that on the inner rings 510, 520 being pressed to either side by the deflection of the connection rope 80 the 70 motor 463 operates automatically as explained below, in whichever direction is needed, to bring the mooring tower to a position directly in the rear of the airship 1. When this is attained the circuit is broken 75 at the rings and the motor stops. It will be seen from the diagram of Fig. 53 that the movement of rings 510 and 520 to the left, causing contact with the left side of 511 and 521 causes current to flow through the motor in one direction while the movement of rings 510 and 520 to the right, causing contact with the right half of rings 511 and 521 reverses the direction of flow of the current through the motor, causing it to turn in an opposite 80 direction. The result obtained by this mechanism is that when the airship moves to one side, to the right, for instance, the mooring mast is moved in the same direction to a position in the rear of the airship; and when the tail of the airship swings to the left the mooring mast is moved correspondingly to the left, thus always maintaining the mooring mast directly to the rearward of the tail end 85 of the airship. Figs. 49, 50 and 51 show a bell-shaped mouth providing entrance of the attachment rope 80 to its point of attachment with the tower. This bell-shape permits deflection of the rope in all direction without causing damage thereto. The device of Figs. 49-53 can be used at a head mooring tower, if desired, in place of the wind vane apparatus shown in Figs. 41-46, in which case the airship itself constitutes a wind vane and on 90 swinging to either side of the predetermined normal relation to the mooring tower sets the tower in motion till its relation is again normal.

In Figs. 54, 55 and 56, an airship 1 is shown attached to a revolvable collar 551 at the top of the fixed mast 541 by means of a universal joint, which by having axes of rotation 553, 554 at right angles to each other provides for movement in any direction. The part 555 rotating in the collar 551 provides for rotating movements of the airship about the longitudinal axis, while the collar 551 revolvable about the center pin 556 of the mast permits swinging of the airship around the mast. Suitable guy lines 542 are used for bracing. 100

For maintaining the airship in a horizontal position while moored to the mast, a long, heavy chain 571 is attached to the airship at a point toward its free end and suspended therefrom. Weight is removed from the airship on the lowering of its free end, and is added thereto on the raising thereof, thus providing a means of stabilizing the airship in its normal horizontal position. In place 105 of the simple chain 571, heavy weights 581

may be attached to a chain 582 or other flexible cable, as shown in Fig. 58.

Fig. 59, shows the airship 1 moored by a line 80 to a carriage 13 adapted for travelling up and down the face of a tower which is rotatable on track 10. Stabilization of the airship while thus moored is provided for by attaching a tank 591 to the airship, at a point toward the free end thereof, by means of tackle 592. A flexible pipe 594 adapted for the flow of liquid therein connects this tank to a second tank 595 located at a lower elevation, preferably on the mooring tower. Automatic control of the flow of liquid between these two tanks is provided either by apparatus 597 located on the airship, which improvement is the subject of a separate application for patent, Serial No. 498,605, or by means of apparatus, the details of which are shown in Figs. 60, 61, and 62. The lower tank 595 which is of air-tight construction is connected by airpipe 601 to the valve 625 and by water pipe 603 to a compression tank 621 which in turn is connected by water-pipe 609 to a cylinder 622. In this cylinder is a piston 623 movable, by variations in head or pressure of the water, against a compression spring 624. To the piston rod 627 is attached the sliding part 626 of the valve 625. Air pipes 601, 602, 603 connect the valve with the tank 595, the compressed air tank 604 and the exhaust respectively. 606 is an air-compressor, driven by motor 607, for supplying compressed air to the system. Automatic means are provided for starting the motor when the air pressure falls below a predetermined amount, and for stopping it when the pressure exceeds a predetermined amount, but as such means are well known to the art, a detailed description of it is not deemed necessary. The action of this stabilizing apparatus is as follows:—Assume that the airship is moored in a position with its longitudinal axis horizontal, that the slide valve is at the mid-position as shown, and that each of the tanks is half full of water, the head or hydrostatic pressure of the water in the upper tank against the piston balancing the action of the spring. When, for any reason, the free end of the airship is forced downward, this pressure is lessened and the piston is pushed by the spring to the left, carrying with it the slide valve and thus permitting air to escape from tank 595 and pipe 601 through exhaust pipe 603 to the atmosphere. This escape of air permits water to flow by gravity from the suspended tank 591 to the tank 595 at lower elevation, and by thus reducing the weight carried by the airship, restores the airship to its normal position. A similar but reverse action takes place when the free end of the ship is raised, for any reason, above its normal position.

In place of having water flow by gravity from the upper tank to the lower a more rapid

stabilizing effect may be obtained by carrying an air pipe from the valve to the upper tank and using the pressure of the compressed air to force water from the upper tank to the lower. As such an arrangement of piping 70 may be simply and easily made, details of it are not herein shown. Also various improvements in the stabilization of airships, described in our separate patent application filed heretofore, on September 6, 1921, Serial 75 No. 498,605, as being applicable broadly to airships are applicable for stabilizing an airship while moored to a tower, and for automatic control of the stabilizing apparatus herein shown. For example, any suitable 80 control comprising liquid container 597 may be arranged lengthwise on the vessel, so that a rise or fall of the rear end will tip it and make some flow or change in pressure of the liquid in this container, which may set in 85 motion automatic machinery to turn the horizontal rudder of the ship. In case a wind is blowing, this may correct the elevation of the rear end. Or the rudder may be deflected by changes in head of liquid in tank 591, as felt 90 in tanks 595, 621 and 622, through suitable electrical connections made by pistons 623, 626 in the motor circuit controlling the rudder (not shown). Or, the motor thus set in motion and referred to as operating a rudder, may operate a pump to shift liquid in the system to or from tank 591. Means may be provided according to details shown in our said other application whereby the rate at which said liquid is made to flow increases 95 and decreases respectively as said free end moves away from and toward its normal elevation with respect to the moored end of the airship.

Assuming that the bow of the airship is 100 fastened at a fixed point, as by an universal joint, one type of which is seen in Figures 55 and 56, showing knuckle joints, and another in Figures 18a and 18b, showing a ball and socket joint, and another in Figures 49 110 and 50 where the rope provides flexibility, all movement of the ship due to change of wind or change of inclination of the longitudinal axis will involve either a movement of the stern mooring or a change in the 115 length of the connection of the ship thereto. Provision may be made for this latter by a rope controlling device illustrated in Figure 38, comprising the motor 372. This motor may be of a type well known in the art, so wired that whether at rest or in motion it exerts a constant torque giving a steady pull predetermined in amount in the mooring rope 80, so long as the current is on. Whenever the pull on the rope as exerted by the airship exceeds this predetermined amount, this motor is turned backward thereby, and acting as a generator puts the current back into the line. On failure of current to flow, a solenoid brake 373 acting on the armature 120

shaft exerts a constant force for holding the rope from being pulled out by a lesser force.

In said Figures 18a and 18b, showing a ball-and-socket-joint mooring attachment, the joint is at the end of a rotatable arm. One member of the joint is a ball carried on a member 163 attached to the bow of the airship. This ball fits into a socket at the end of the arm 165, which arm is rotatable about the mast 556. The walls of the socket are split, having a hinged portion 164 which opens to permit entrance of the ball into the socket and which, when closed, and fastened by the pin 168, holds the ball in the socket.

Figs. 63 and 64 illustrate a collapsible protective roof for housing. The airship 1 is shown moored between two towers 9 and resting on a cradle 280. The towers and cradle are movable on tracks 10 and 270 respectively. Suspended between the towers are three main cables 631 which support a flexible fabric roof 630 by means of travellers 633 and attachment pieces 635. Ropes 632 to which are fastened clamps 634 with power operated winches 636 provide means for handling the flexible roof over the airship. For greater ease in thus handling the roof, it may be divided vertically at the middle of its length, as shown in Figure 64, and a set of hauling lines 632 used for handling each half. In operation, the airship is brought up head on to the wind and moored to one of the towers 9. The other tower is then brought around on its track to the rear of the airship and the tail end of the ship fastened thereto; the cradle car 280 is also brought to a position below the ship, after which the ship may be lowered under control onto the cradle. Each tower carries one half of the roof covering in collapsed condition, with the several ropes 631, 632 reeved through the travellers 633. The corresponding parts of these ropes are joined together after which they are stretched tight and the roof is stretched over the airship by the winches pulling on ropes 632. By maintaining the airship while moored and its roof covering over it, head on to the wind, stresses in the airship and its mooring equipment are greatly reduced from what would otherwise occur. The invention further provides for the use of a similar flexible roof covering permanently stretched between stationary supports and the bringing of an airship on its cradle to a position beneath this roof.

What we claim is:

1. A self-supporting mooring mast for airships comprising a tower, a connecting device associated with said tower with which the airship may be connected, said connecting device adapted to be moved longitudinally along the tower while the airship is connected thereto and to be moved circumferentially about the axis of said tower.

2. In equipment for housing airships, the combination of a housing chamber; a roof, movable so as to open and to close the chamber; and tower means for controlling the descent of an airship into and its ascent from the chamber.

3. In equipment for housing airships, the combination of a shelter pit of suitable size to house an airship; a roof, and ways on which the roof may be moved so as to open and close the pit; means for moving the roof along said ways; and a tower near said pit for mooring the airship.

4. In equipment for housing airships, the combination of a subterranean housing structure having a top which is movable so as to permit an airship to enter said structure by a downward movement; means for moving the top to open and to close said structure; and tower means for controlling the descent of an airship into and the ascent of same from the enclosing structure.

5. In equipment for housing airships, the combination of a housing chamber; means to cover and uncover said chamber; a movable tower located at one end of said chamber; a way extending up and down said tower; a continuation thereof at the end of said chamber; a carriage movable along said way; power means controlling said carriage movements; and tackle for fastening an airship to said carriage; whereby said airship may be held and, while thus held, be brought to a position over said chamber and lowered into said chamber under control.

6. In equipment for housing airships, the combination of a housing chamber and means to cover and uncover said chamber; a tower capable of revolving about a fixed center located at one end of said chamber; two ways, one extending up and down the tower; the other forming a continuation of the tower way, at the end of said chamber; a carriage movable along said ways; power means for controlling the movements of the carriage; and tackle for fastening an airship to the carriage on the tower; whereby said airship may be held, and while thus held may be brought to a position over said chamber, and may be lowered into said chamber under control.

7. In equipment for mooring and housing airships at a station, the combination of a mooring tower; a hangar within which said airship may be housed; and means for lowering an airship to a position within the hangar and for elevating it therefrom while the airship is moored to the tower.

8. In equipment for mooring airships, the combination of a mooring tower, a fixed way extending up and down said tower, a carriage movable along said way, and means for controlling such movement.

9. In equipment for mooring airships, the combination of a rotatable mooring tower; a mooring element movable vertically thereon,

said element having means which is flexible, as regards its elevation of angle above the horizon, for its connection to the airship; and mechanical means by which said element
 5 may be raised and lowered under control.

10. A mooring mast rotatable about its own axis.

11. In equipment for mooring airships, the combination of a mooring tower; a mooring
 10 element cooperating with the exterior surface of said tower; and mechanical means by which said mooring element may be raised and lowered under control.

12. A self supporting mooring mast for
 15 airships comprising a rotatable tower, a connecting device associated with said tower with which the airship is connected, said connecting device adapted to be moved up and down the tower while the airship is connected thereto.

13. A mooring mast for airships comprising a rotatable tower, and, associated therewith, a connecting device adapted to be moved longitudinally of the tower.

25 14. A mooring device for airships comprising a revolving tower, means for connecting an airship to said tower when approaching from any direction, said tower being self-sustaining and forming a laterally resisting element which of itself resists the pull of the airship.

35 15. In equipment for housing airships, the combination of a housing structure having a top which is movable so as to permit an airship to enter said structure by downward movement; means for so moving the top to open and to close said structure; an auxiliary structure comprising a mooring outside of the housing; means for attaching an airship thereto; and power means applicable to said attachment means whereby an airship may be brought to a position over the said housing structure.

40 16. In equipment for housing airships, the combination of a housing chamber; and rotatable means for controlling the descent of an airship into and its ascent from the chamber.

50 17. In equipment for housing airships, the combination of a subterranean housing chamber; and tower means for controlling the descent of an airship into and its ascent from the chamber.

55 18. A mooring mast comprising a tower, a track on said tower, and a carriage movable on said track, said carriage being adapted to hold one end of an airship to said tower.

Signed at New York, N. Y., this first day of July, 1921.

60 WILFRID V. N. POWELSON.
WARREN TRAVELL.
